UNITED STATES PATENT OFFICE.

JOSEPH CAMERON, OF MINNEAPOLIS, MINNESOTA.

ELECTROTHERAPEUTIC APPARATUS.

Application filed May 4, 1925. Serial No. 27,823.

To all whom it may concern:

Be it known that I, JOSEPH CAMERON, a citizen of the United States, residing at Minneapolis, in the county of Hennepin and

5 State of Minnesota, have invented certain new and useful Improvements in Electro-therapeutic Apparatus; and I do hereby declare the following to be a full, clear, and exact description of the invention, such as

10 will enable others skilled in the art to which it appertains to make and use the same.

My invention has for its object to provide an electro-therapeutic apparatus in which electrical energy is utilized both as

15 heat and light for healing purposes and for the treatment of fractures and diseases. Said invention further provides means for cooling the patient's wrist to keep his blood at normal temperature, which temperature

20 would otherwise be raised by the treatment.

The apparatus is held suspended over that part of the patient's body to be treated and includes a fan for producing a blast of cool air, a portion of which is constantly

25 delivered onto the patient's wrists through wristlets applied thereto, and under the action of a rotary pulsator or vibrator, the remaining air from the fan is delivered in a rapid succession of air pulsations or vibrations into a heating chamber. In this heating

30 chamber is a heating element, preferably in the form of a coil, the temperature of which is controlled by a rheostat, as shown, applied on the top of the casing.

35 Below the heating chamber is a light chamber that contains light bulbs and a reflector having a skeleton dome. These hot air pulsations or vibrations are delivered from the heating chamber into the light chamber

40 through the skeleton dome, which is preferably made up of vertically spaced concentrically located reflecting lenses of upwardly decreasing diameter. The light bulbs in the light chamber are preferably spaced

45 around an axially located focusing lens that is axially aligned with a focusing tube through which latter the heat wave and light rays are delivered to the point or surface on the patient's body to be treated. The delivery through the focusing lens and focusing tube of the light rays will be constant, but the heat waves will be delivered with a sort of pulsating or vibrating action due to the action of the rotary pulsator or vibrator.

50 In the accompanying drawings, which il-

lustrate the invention, like characters indicate like parts throughout the several views.

Referring to the drawings:

Fig. 1 is an elevation of the apparatus 60 with some parts broken away and sectioned;

Fig. 2 is a view of the apparatus principally in central vertical section, on an enlarged scale;

Fig. 3 is a transverse section taken on the 65 line 3—3 of Fig. 2;

Fig. 4 is a fragmentary detail view in central vertical section taken on the line 3—3 of Fig. 1; and

Fig. 5 is a wiring diagram. 70

As one means of supporting the apparatus, I provide a tubular standard 6 mounted on a truck 7 and having a tubular horizontal arm 8. A carriage 9 is mounted to travel on track rails 10 formed on the sides of the arm 8 and a grooved wheel loosely journaled on said carriage and located within the tubular arm 8. A cable 12, within the arm 8, runs over the grooved wheel 11, and a grooved wheel 13 journaled in the tubular standard 6. One end of this cable 12 extends downward into the tubular standard 6 and has secured thereto a plurality of counterweights 15, and its other end extends downward through a longitudinal slot 16 in the under side of the arm 8 and is provided with a plurality of branch cables 17 from which the apparatus is suspended. 75

The apparatus includes a vertically disposed cylindrical casing 18 the upper end of which is open and the lower end of which is closed with the exception of a focusing tube 19. This casing 18 is held suspended from the arm 8 by the cable 12 which is attached thereto by the branch cables 17. 80 These branch cables are secured to the casing 18 at circumferentially spaced points by eye-equipped lugs 20. 85

Within the casing 18 is an upper fan housing 21, an intermediate heating chamber 22, and a lower light chamber 23 from the bottom of which the focusing tube 19 leads. In the top of the fan housing 21 is a large axially located air intake eye 24 and in the bottom thereof is a pair of circumferentially spaced air discharge ports 25. In the bottom of the housing 21 are two diametrically opposite air pockets 26, from which lead conduits 27 having nipples 28, for a purpose 100 which will presently appear. 105

110

Within the casing 18 is an electric motor 29 secured by a spider 30 to said casing above the fan housing 21 and held with its armature shaft 31 in a depending position 5 and axially located in respect to the casing 18. A fan 32 is mounted in the fan housing 21 and driven from the armature shaft 31 to which it is secured. Also secured to the armature shaft 31 and driven therefrom 10 is a rotary pulsator or vibrator 33 located in the fan housing 21 through the bottom of which said armature shaft projects. This pulsator or vibrator 33 (hereinafter referred to as a pulsator) is in the form of a flat disc 15 located just under the bottom of the fan housing 21 for rotation in a plane parallel thereto and having two circumferentially spaced ports 34 arranged to be intermittently brought into registration with the ports 25 20 leading from the fan housing 21 under the rotation of said pulsator by the motor 29.

Mounted within the heating chamber 22, near the top thereof, is a heating element 35 in the form of a coil, and interposed between the pulsator 33 and the heating element 35 is a heat deflecting hood 36. A cluster of electric light bulbs 37 is mounted in sockets 38 circumferentially spaced around the focusing tube 19 and secured in the bottom 30 of the light chamber 23. Axially located within the light chamber 23 above the focusing tube 19, is a focusing lens 39 having on its frame 40 a pair of collars 41 slidably mounted on a pair of upright diametrically opposite posts 42 and secured thereto in different vertical adjustments by set screws 43.

Located over the light bulbs 37 and focusing lens 39 is a conically formed reflector 45 having a large axial opening over which is located a skeleton dome comprising a plurality of concentric rings 46 and a top plate 47 vertically spaced to leave air passages 48 therebetween. This reflector 44 and dome 45—47 afford a partition which separate the heating chamber 22 from the light chamber 23. For controlling the temperature of the heating element 35, there is provided a rheostat 49 mounted in the top of the casing 18 but spaced from the sides thereof to leave an air intake passageway 50.

The temperature of the heating chamber 22 is registered by a thermometer 51 mounted in a casing 52 secured to the outside of the casing 18, and the upper end of which casing 52 is connected to the fan housing 21 by a conduit 53, and the lower end of which is connected to the heating chamber 22 by a conduit 54. Obviously air is free to circulate around the thermometer 51 through the casing 52 and conduits 53 and 54. Access may be had to the interior of the casing 18, between the electric motor 29 and rheostat 49, through a hand hole normally closed by a cover plate 55. To keep a patient's blood

at normal temperature during the treatment by the apparatus, cool air, from the fan 32, is applied to his wrists, as previously stated, by means of wristlets 56 having nipples 57 connected by hose sections 58 to the nipples 28. Obviously, air entering the pockets 26 from the fan 32 will pass through the conduits 27, nipples 28, hose sections 58, and nipples 57 to the patient's wrists. The wristlets 56 are held on a patient's wrist by means of spring-acting clamps 59.

Referring now to the wiring diagram shown in Fig. 5, the numeral 60 indicates lead wires connected by a socket 61 to a key-equipped lamp socket 62, attached to a duplex lamp cord 63 leading from any suitable source of supply. The electric motor 29 is connected to the lead wires 60 by a pair of branch wires 64 in one of which is interposed a switch 65. The heating element 35 is connected to the lead wires 60 by a pair of branch wires 66 in one of which is interposed the rheostat 49 and in the other of which is interposed a switch 67. The light bulbs 37 are connected parallel to the lead wires 60 by a pair of branch wires 68 in one of which is interposed a switch 69.

During the treatment of a patient by the apparatus, he lies on a couch 70 over which said apparatus is suspended. The counterweights 15 hold the apparatus where positioned at different elevations, and permit the same to be raised or lowered, and the carriage 9 and truck 20 permit the apparatus to move horizontally into different positions over a patient's body.

Preferably, the concentric rings 46 and the cover plate 47 have reflecting surfaces within the light chamber 23, and the back of the reflector 44 within the heating chamber 22 is covered with a suitable insulating material 71. The entire casing 18 is encased by a finishing shell 72 between which and said casing is an insulating material 73.

What I claim is:

1. A casing having a fan housing, a heating chamber and a light chamber, said fan housing having a discharge port leading to the heating chamber and said light chamber having a focusing opening, in combination with a fan mounted in the fan housing, of a heating element mounted in the heating chamber, and a light bulb mounted in the light chamber.

2. The structure defined in claim 1 in further combination with a lens at the focusing opening.

3. The structure defined in claim 1 in further combination with an axially adjustable lens at the focusing opening.

4. The structure defined in claim 1 in further combination with a pair of wristlets having hose connections leading from the fan housing.

5. The structure defined in claim 1 in

further combination with a pair of clamp-acting wristlets having hose connections leading from the fan housing.

6. The structure defined in claim 1 in further combination with a rotating disk with sectorial incisions to generate pulsations of air current between the fan and the heating element and light bulb.

7. The structure defined in claim 1 in further combination with a rotating disk with sectorial incisions to generate pulsations of air current mounted in the heating chamber between the fan and the heating element, and a reflector for the light bulb.

15. 8. The structure defined in claim 1 in further combination with a rotating disk with sectorial incisions to generate pulsations of air current mounted in the heating chamber between the fan and the heating element, a reflector for the light bulb, and a pair of wristlets having hose connections leading from the fan housing.

9. The structure defined in claim 1 in further combination with a rotating disk 25 with sectorial incisions to generate pulsations of air current mounted in the heating chamber between the fan and the heating element, a reflector for the light bulb, said housing having a pair of air pockets, and a 30 pair of wristlets having hose connections leading from the air pockets.

10. The combination with an upright casing having an upper fan housing, an intermediate heating chamber and a lower light 35 chamber, said fan housing having a discharge port leading to the heating chamber and said light chamber having a focusing

opening, of a fan mounted in the fan housing, a heating element mounted in the heating chamber, a cluster of light bulbs surrounding the focusing opening, a reflector in the light chamber for the light bulbs, a rotating disk with sectorial incisions to generate pulsations of air current mounted in the heating chamber between the fan and the heating element, an electric motor for driving the fan and said disk, and a pair of wristlets having hose connections leading from the fan housing.

11. The structure defined in claim 10 in further combination with an overhead carriage, and means for suspending the casing from the carriage.

12. The structure defined in claim 10 in further combination with an overhead carriage, and means for suspending the casing from the carriage and vertically adjusting the same.

13. The structure defined in claim 10 in which the reflector is conically arranged and 60 provided with an axial opening, said reflector having a skeleton dome through which the heat waves pass from the heating chamber to the light chamber.

14. The structure defined in claim 10 in which the reflector is conically arranged and provided with an axial opening, said reflector having a skeleton dome through 65 which the heat waves pass from the heating chamber to the light chamber, said dome comprising a plurality of vertically spaced concentric rings.

In testimony whereof I affix my signature.
JOSEPH CAMERON.
